ATTORNEYS.

UNITED STATES PATENT OFFICE.

MAX KRISIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

MACHINE FOR MAKING CORDED BRAID.

Original application filed October 10, 1927, Serial No. 225,320. Divided and this application filed February 15, 1929. Serial No. 340,161.

This invention relates to an improved braiding machine adapted particularly for producing the improved braid set forth in my copending application Serial No. 225,320, 5 of which the present application is a division; the complete invention involving the interweaving of simultaneously produced flat and tubular braidings, with a portion of the width of the flat braiding extending 10 diametrically of the tubular braiding and interwoven with the latter at spaced-apart intersections of the two braidings; as fully described in connection with the accompanying drawings.

15 Fig. 1 is a side view, and Fig. 2 a cross-sectional view, indicating a particular integrally formed braid which my improved machine is adapted to produce; and Fig. 3 is a diagrammatic view showing the novel 20 arrangement of carrier courses provided in a braiding machine of otherwise ordinary construction, to enable the production of such novel braid.

A composite braid, similar in a general 25 way to that indicated in Figs. 1 and 2, has heretofore been produced by securing to opposite sides of an ordinary flat braid, as by means of sewing, separately made cord braidings which provide the cord effect particularly desired on opposite sides of the 30 edge portion of the flat braid shown. Effort has also been made to produce such cord effect in an integral construction, by interweaving with the flat braid transverse 35 looping threads arranged to fold around and secure to the sides of the flat braid, suitable longitudinal filler threads, so as to provide a reinforcing longitudinal rib on each side of the braid; such integral construction being 40 readily produced upon a known type of braiding machine having a transverse carrier course adapted to carry such looping threads across the path of the usual flat-braiding carriers. I have found however 45 that a cord effect having the functional characteristics of the composite braid referred to and which are practically required in such braid, cannot be provided by such an integral formation of the side reenforcement as is above referred to; and my invention therefore consists in providing for the 50 production of an actual braided-cord effect integral with the main flat braid, and for

satisfactorily producing such an integral structure continuously and rapidly.

To this end I provide for simultaneously producing a flat braid 10, extending the full width of the fabric, and a tubular braid having a portion 10^a of the flat braid extending diametrically through it so as to be 55 intersected by the crossing wall of the tubular braid at two points 13 and 14 respectively, spaced-apart to correspond with the diameter of the tubular braid; the interbraided threads which form the tubular 60 braid, crossing the flat braid and being interwoven therewith at each of said spaced-apart intersections 13 and 14; and the side portions of the tubular braid which overlie the respective sides of the diametral flat- 65 braid portion forming in connection with said flat-braid portion 10^a, twin tubular reinforcements 11^a 11^b on opposite sides of the flat braid. To give desired cord effect to these tubularly braided reinforcements on 70 each side of the flat braid, any desired number or size of longitudinal fillers are provided, within each tubular reinforcement as indicated at 15, 15, and also at each circle- 75 center of the braiding courses as indicated at 16, 16, as desired.

My improved machine for making the improved braid above described, is of ordinary and well known construction excepting as to the special carrier courses provided, and the 80 diagrammatic showing in Fig. 3 therefore simply indicates these carrier courses without unnecessary showing of known detail. The course for the flat braiding carriers *f f* is indicated by the full lines *a*, while the 85 paths of the oppositely moving tubular braiding carriers *t* and *t'* are indicated by light dotted lines and heavier dotted lines *b* and *c* respectively; these paths *b* and *c* intersecting as usual on the side braiding circles 20—21 90 and 22—23, but providing ordinary cross-overs for the carriers *t*, *t'* between the race-circles 24—25, and 26—27, so that all the carriers on paths *b* and *c* pass the like cross-over for carriers *f f* of the flat-braiding 95 course *a*, as guided by the usual star plates *s s* at the points of intersection, and so interweave with the flat braid forming the top edge of the latter as indicated at 13, and also at a point 14 spaced-apart two race- 100 circles therefrom. Thus the tubular braid- 105

ing effected on the courses *b* and *c*, provides twin filler spaces on the sides of the diametrical dividing portion 10^a of the flat braid formed; between which portion and the braided side walls of the tubular braiding, desired longitudinal fillers 15 may be introduced so as to form substantial cord reinforcements of desired body and firmness.

10 What I claim is:

A braiding machine comprising a tubular-

braiding carrier course having separate series of carriers continuously traversed thereon in opposite directions, and an intersecting flat-braiding carrier course having carriers returningly traversed thereon; the respective carriers being simultaneously operated and said courses being provided with carrier cross-overs at their separated points of intersection. 15

In testimony whereof I affix my signature.
MAX KRISSIEP. 20
